UNITED STATES PATENT OFFICE.

ROBERT O. BOARDMAN, OF GRAND RAPIDS, MICHIGAN, ASSIGNOR TO MERGENTHALER LINOTYPE COMPANY, A CORPORATION OF NEW YORK.

TYPOGRAPHICAL MACHINE.

1,088,397.

Specification of Letters Patent. Patented Feb. 24, 1914.

Application filed March 20, 1913. Serial No. 755,588.

To all whom it may concern:

Be it known that I, ROBERT O. BOARDMAN, a citizen of the United States, residing at Grand Rapids, in the county of Kent and 5 State of Michigan, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print, and then assembled in line, the composed line transferred to the face of a mold, the mold filled with molten metal to 15 form a slug or linotype against the matrices which produce the type character thereon, and the matrices thereafter returned through a distributing mechanism to the magazine from which they started.

20 More particularly, it relates to machines of this kind wherein are employed distributing mechanism and a plurality of magazines, and in connection therewith means for transferring the matrices from the distributing mechanism to the proper magazine. In the present instance, these transferring means comprise a conductor or holder, to which the matrices are delivered according to letter by the distributing mechanism, and 25 in which they are temporarily held, and then subsequently delivered to the appropriate magazines through adjustable channels or switching devices. The adjustment of the channels or switching devices is controlled by the form of the type or matrices, these being suitably varied in accordance with 30 their particular font and the magazine in which they are stored, in such manner that the channels or switching devices will be 35 shifted to connect the holder or conductor always with the proper magazine.

In the accompanying drawings, I have shown my invention in preferred form and by way of example, and as applied to a linotype machine. Obviously, however, many 40 variations and alterations may be made therein, and in its mode of application, which will still be comprised within the spirit of my invention. Thus, it may be 45 adapted to typographical machines of other

kinds, such as type setters and type casters, or those which handle type or dies instead of matrices. Generally speaking, I desire it to be understood that I do not limit myself to any specific form or embodiment, except 60 in so far as such limitations are specified in the claims.

Referring to the drawings: Figure 1 is a vertical section through the distributing mechanism, etc., of a linotype machine having my invention embodied therein; Figs. 2, 3 and 4, are similar views, showing certain of the parts in different positions; Fig. 5 is a detached perspective, showing the relation of the switches, partitions, etc.; Fig. 6 is a front view, partly broken away, and partly in section on the line 6—6 in Fig. 1; Fig. 7 is a detached perspective, showing the relation of a single disk, switch lever, escapement lever, etc.; Fig. 8 is a detail section on the line 8—8 in Fig. 1; and Fig. 9 illustrates matrices of different fonts, as contained in the respective magazines.

The matrices X are moved along the distributor rail A by the conveying screws A¹ 80 and drop into the channeled holder or intermediate magazine B, from which they are subsequently released by escapement devices, and transferred by switching means to and through the channel entrance Y into the individual magazines to which they belong. In other words, the matrices are distributed, first, according to letter and, subsequently, according to font. In the present instance, and by way of example, three magazines, 90 B¹, B², B³, are illustrated, and in Fig. 9 are shown matrices X of three different styles or fonts, formed respectively with notches X¹, X², X³, of variant depth, to correspond to the several magazines. The extent of adjustment of the switching means is controlled by these notches in such manner 95 that they will deliver a matrix of any given font into the corresponding magazine.

The previously mentioned escapement devices, appertaining to the channeled holder B, comprise each an upper pawl C¹ and a lower pawl C² connected to the elongated lever C, whereby the pawls are alternately projected into and withdrawn from the 105 channels, and the release of the matrices therefrom is controlled. The lower pawl C² is adapted to engage in the notches X¹, X², X³ of the matrices, and the different extent 110 of this movement is utilized to control the

switching means next to be described. These switching devices consist of a plurality of individual switches D, four being illustrated in the present instance, pivotally mounted at 5 d at their lower extremities in correct relation to the entrance Y. There is a series of such switches D corresponding to each channel of the holder B and the corresponding set of channels of the entrance Y, these channels being made practically continuous by 10 the interposition of partitions D^5 between the holder B and entrance Y, the partitions D^5 being supported in any suitable manner, as for instance by the engagement of notches 15 therein with the transverse frame portions D^6 (see Fig. 8). The pivotally mounted switches D thus constitute a series of channels or throats D^1 , D^2 , D^3 , one for each of the magazines B^1 , B^2 , B^3 , and are so arranged 20 that any selected one of the said channels may be brought into operative relation to the holder B so as to form a continuous passage therefrom to the proper magazine. The upper ends of the switches 25 D are pivotally connected at d^1 to the sliding bar E^1 , which rests upon the partition D^1 , and is connected to the switch lever E, it being understood as previously stated that there is a complete set of these elements for 30 each channel in the holder B. To permit the free shifting action of the switches D, they are each made in two relatively movable parts connected by a telescopic joint D^{20} .

Connecting the upper arm of the escapement lever C and the switch lever E is a 35 spring H, which tends to draw the two levers together, and also to move the lower pawl C^2 into the matrix channel, the extent of the relative movement of the two levers 40 being limited by the contact of the lever C with a stop G upon the lever E. The lever C is also provided with a shoe or cam piece M, located in position to be successively acted upon by the projections N and O on the 45 rotating disk K, whereby the lever C and pawls C^1 and C^2 are moved against the force of the spring H to effect the proper operation of the escapement. The switch lever E is pivoted at its upper end at e to the 50 framework, and is provided with a second spring F, whereby the lever E, slide E^1 and switches D are normally held in their retracted position (see Fig. 1), at which time the passage D^3 of the magazine B^3 is brought 55 into operative relation to the holder B. It should be noted that the spring H is stronger than the spring F and consequently controls the latter at certain points of operation.

As previously stated, the escapement pawl 60 C² moves to different extents in relation to the matrices X, this being governed by the depth of the notch X¹, X² or X³ therein; and consequently the upper end of the lever C is correspondingly moved. The different 65 positions of the lever C are utilized to gov-

ern the adjustment of the switch lever E, which is normally moved toward it by the spring H until the stop G is brought into engagement therewith. Thus, for instance, Fig. 1 shows the pawl C² as engaging a deep 70 notch X³, and the upper end of the lever C consequently in its innermost position, and therefore the outer switching channel D³ of the magazine B³ in operative relation to the holder B. In Fig. 4, the pawl C² is shown as 75 engaging a shallow notch X¹, at which time the upper end of the lever C is in its outermost position, and therefore the channel D¹ of the magazine B¹ is in operative relation to the holder B. 80

For the positioning of the switches D to connect the holder B with the appropriate magazines, and to permit the proper actuation of the escapement devices, it is necessary that the switch lever be held in its various adjusted positions. This result is secured by providing the lever E (see particularly Fig. 7) with a cam roll J, located in line with the stop G and at the opposite side therefrom, which roll J is engaged and held 85 by one or another of a series of cam grooves K¹, K², K³, formed on the disk K, the said grooves being appropriately positioned to correspond respectively to the operative relation of the switch channels D¹, D², D³ to 90 the holder B. These grooves extend throughout only a portion of the disk K, so as to permit the transfer of the roll J to one or another of them, as the next matrix is 95 presented to the lower escapement pawl or 100 feeler C². The disks K, one for each switch lever, are mounted on the transverse shaft L which is actuated in any desired manner, as for instance by the band wheel L¹. The rotation of the disk K not only serves to lock 105 the switch lever in its adjusted positions, but also brings the projections N and O into operative relation to the shoe M on the lever C, so as to actuate the escapement, while the switching devices are held against movement, in the manner now to be described. 110

In Fig. 1, the parts are shown with the pawl or feeler C² in engagement with the deep notch X³ of a matrix X, at which time the upper end of the lever C, the lever E, 115 and slide E¹ are in their innermost positions, thus bringing the channel D³ of the magazine B³ into relation to the holder B. At this time the roll J is in readiness to engage the corresponding cam groove K³, and the 120 subsequent rotation of the disk K therefore causes the switching means to be held in their adjusted position during the actuation of the escapement devices. As the disk K rotates (see Fig. 2), its projection N contacts with the shoe M and swings the lever C about its pivot, thus disengaging the pawl C² from the lowermost matrix and permitting it to drop into the channel D³, and at 125 the same time projecting the pawl C¹ under 130

the upper ear of the following matrix all as indicated by full lines. As the disk K continues its rotation, the projection N passes beyond the shoe M, and under the influence 5 of the spring H, the escapement assumes the position indicated by dotted lines in Fig. 2, namely, with the upper pawl C¹ retracted and the lower pawl projected, which permits the next matrix to fall upon and be 10 sustained by the lower pawl. The disk K still continues its rotation until its other projection O contacts with the shoe M, which engagement again reverses the position of escapement, namely, by withdrawing the 15 lower pawl C² and projecting the upper pawl C¹, as shown in Fig. 3. This operation releases the matrix previously sustained by the pawl C², and other means are therefore necessary to prevent its premature delivery. 20 This I preferably effect by the movement of the switch D under the bottom edge of the matrix, which movement is secured by a slight bend k in the cam grooves, which are otherwise substantially circular in their direction. As the disk K continues its rotation, the projection O also passes beyond the shoe M, and the spring H again reverses the 25 position of the escapement, namely, by withdrawing the upper pawl C¹ and projecting the lower pawl C², when the parts have completed their cycle of operation and are in the 30 position indicated in Fig. 4. It should be noted, as shown in Fig. 4, that the matrix X now in engagement with the lower pawl C² is formed with a shallow notch N¹, and consequently the upper end of the lever C is held in its outermost position, and due to the action of the spring H, the lever 35 E is moved in such manner as to register the channel D¹ of the magazine B¹ with the holder B. The roll J on the inner side of the lever E is now in position to be engaged by the outer cam groove K¹ of the disk K, whereby the switching elements will be 40 again locked during the escapement operation, in the manner already described.

As previously stated, I have shown my invention in preferred form and by way of example, and in connection with a linotype 50 machine. It will be seen that one of the principal features involved is the provision of a temporary holder and movable distributing devices controlled in their position by the form of the type or matrices, whereby 55 the matrices are temporarily stored in the holder and from which they are subsequently delivered to the appropriate channels in a plurality of magazines. In the specific form discussed, there is an individual 60 and independently-movable conductor for each channel of each of the magazines, but obviously such arrangement is not essential, as no invention would be involved in laterally connecting a plurality thereof. This 65 and many other modifications will suggest

themselves to those skilled in the art without departure from the scope of the invention.

Having thus described my invention, its construction and mode of operation, what I claim and desire to secure by Letters Patent of the United States, is as follows:

1. In a typographical machine, the combination of a distributing mechanism, a plurality of magazines for the type or matrices, an intermediate holder wherein the type or matrices are temporarily stored, and a plurality of movable channels or throats, through which the type or matrices pass, one for each magazine, to receive the type or matrices directly from the holder and deliver them to the magazines. 75

2. In a typographical machine, the combination of a distributing mechanism, a plurality of magazines for the type or matrices, an intermediate holder wherein the type or matrices are temporarily stored, and a plurality of movable channels or throats, through which the type or matrices pass, one for each magazine, to receive the type or matrices directly from the holder and deliver them to the magazines, the said movable conductors being controlled as to their position by the form of the type or matrices. 85

3. In a typographical machine, the combination of a plurality of magazines adapted to contain different fonts of type or matrices, distributing mechanism to separate the type or matrices according to letter regardless of font, a holder wherein the separated type or matrices are temporarily stored, and a plurality of switching devices to deliver the separated type or matrices from the holder into one or another of the magazines according to font, the said devices being connected together so as to be movable as a whole, and controlled in their movement by the form of type or matrices. 95

4. In a typographical machine, the combination of a plurality of magazines adapted to contain different fonts of type or matrices, distributing mechanism to separate the type or matrices according to letter regardless of font and a plurality of switching devices to deliver the separated type or matrices into one magazine or another according to font, the said devices being connected together so as to be movable as a whole and controlled in their movement by the form of the type or matrices. 110

5. In a typographical machine, the combination of a distributing mechanism, a plurality of magazines for the type or matrices, and means for delivering the type or matrices from the distributing mechanism 115 to their respective magazines, the said means including escapement devices serving to control both the passage of the type or matrices and the operation of their delivery means. 125

6. In a typographical machine, the combi- 130

- nation of a distributing mechanism, a plurality of magazines for the type or matrices, and means for delivering the type or matrices from the distributing mechanism to their respective magazines, the said means including a movable conductor and escapement devices which control both the passage of the type or matrices and the position of the said conductor.
- 10 7. In a typographical machine, the combination of a distributing mechanism, a plurality of magazines for the type or matrices, and means for delivering the type or matrices from the distributing mechanism to their respective magazines, the said means including a holder wherein the type or matrices are temporarily stored, a movable conductor to connect the holder with one of the magazines, and escapement devices which control both the position of the movable conductor and the release of the type or matrices from the holder.
- 15 8. In a typographical machine equipped with type or matrices of variant forms, distributing mechanism comprising escapement devices which control both the release of the type or matrices therefrom and their further distribution according to their form.
- 20 9. In a typographical machine equipped with type or matrices of variant forms, the combination of a plurality of magazines therefor and distributing mechanism, the said distributing mechanism being provided with escapement devices which control both
- the release of the type or matrices therefrom 35 and the delivery thereof to their appropriate magazines according to their form.
- 10 10. In a typographical machine, the combination of a distributing mechanism, a plurality of magazines for the type or matrices, 40 a holder wherein the type or matrices are temporarily stored, and a plurality of movable conductors to connect the holder with one or another of the magazines, escapement devices controlling both the position of the 45 movable conductors and the release of the type or matrices from the holder, and means for locking the conductors in their proper position during the releasing operation of the escapement devices.
- 11 11. In a typographical machine, the combination of a plurality of magazines for the type or matrices, a holder to receive the type or matrices from the distributing mechanism, escapement devices to control 50 the release of the type or matrices therefrom, and a plurality of movable conductors to convey the type or matrices from the holder to their respective magazines, the said conductors serving to hold the type or matrices within said holder at one point of operation of the parts.
- In testimony whereof I affix my signature in presence of two witnesses.
- ROBERT O. BOARDMAN.
